GRINDING MACHINE WITH WHEEL SHIFTING MEANS

Walter F. Ross, Springfield, Vt., assignor to The Fellows Gear Shaper Company, Springfield, Vt., a corporation of Vermont

Application February 6, 1941, Serial No. 377,627

9 Claims. (Cl. 51—55)

This invention relates to grinding machines of the type having a rotatable abrasive wheel. Its object is to shift the abrasive wheel in the course of its action so as to avoid repeated tracking of the same point on the face of the wheel continuously in the same path. This object may be otherwise expressed as being to cause tracking of the abrasive wheel in constantly varying paths, whereby to secure non-duplicating motions of the wheel to produce free cutting and, in large measure, avoid pronounced wheel scratches in the work.

The principles in which the invention consists may be applied in many different machines for performing a wide diversity of grinding operations on different work pieces. The application or use here shown for illustration is in connection with a machine for generating and finishing, by grinding, the tooth face curves of gears, gear shaper cutters, gear finishing tools, and the like. Such illustrated embodiment is described herein to disclose the principles for which I desire protection, by reference to a concrete example and with the understanding that such principles are covered herein generically for all combinations in which they may be applied, as well as in the specific embodiment thus disclosed.

Briefly, these principles comprise the combination with a grinding wheel, and means for driving it continuously at suitable cutting speed, of auxiliary means acting on the holder to shift such wheel progressively through limited distances in one or more directions other than the path of normal travel.

In the drawings herewith—

Fig. 1 is a vertical section of the upper part of a machine for grinding gears and the like to which I have applied one embodiment of this invention;

Fig. 2 is a vertical section of the machine taken on line 2—2 of Fig. 1;

Fig. 3 is a cross section taken on line 3—3 of Fig. 2 and shown on a larger scale;

Figs. 4 and 5 are horizontal sections taken on lines 4—4 and 5—5 respectively of Fig. 3;

Figs. 6, 7 and 8 are cross sections taken on line 6—6, 7—7 and 8—8 respectively of Fig. 4;

Fig. 9 is a detail vertical section taken on line 9—9 of Fig. 5;

Fig. 10 is a fragmentary view showing a modified form of cam adapted to be substituted for the cam shown in Fig. 9;

Fig. 11 is a partial view similar to Fig. 3 showing an additional feature adapted to be combined with the machine illustrated in the preceding figures;

Fig. 12 is a view on a larger scale of a part of the additional feature represented in Fig. 11;

Fig. 13 is a cross section taken on line 13—13 of Fig. 12.

Like reference characters designate the same parts wherever they occur in all the figures.

For the purpose of convenient explanation, an embodiment of this invention has been shown in the drawings as applied to a gear generating machine of the type described in the patent to Edwin R. Fellows No. 1,743,335 granted January 14, 1930. In such a machine a work piece W, which may be a gear, a gear shaper cutter, a shaving tool, or other article having peripheral teeth, is rolled across the rim of a grinding wheel G in such manner that the wheel rim projects between two teeth of the work piece, and the margin of its side face engages the face of the contiguous tooth, cutting and generating the tooth to prescribed contours and dimensions. The spindle d on which the work piece is secured passes through a housing e, which is mounted by means of tubular trunnions f and g in a swing frame h supported by the pivot ends of a bar i. A combined gear segment j and cam k is secured to the trunnion f by means of a rigidly connected stud l. A rack bar m meshes with the gear segment j and is connected with one arm of a lever n. The cam element bears against a stationary abutment o.

The lever n, being oscillated about its pivot p, imparts back and forth rotary movement to the gear segment j, cam k, housing e and work spindle d. The cam k, reacting against the abutment o, causes the entire assemblage, including the swing frame h, to swing about the axis of bar i, thus causing the work piece W to roll across the rim of the grinding wheel. A side face of the grinding wheel adjacent to its circumference performs the cutting action on the work, and the wheel is rotated at suitable cutting speed about its axis A. The principles in which the invention consists comprise means for gradually and progressively shifting the grinding wheel back and forth in one or more paths coinciding with its working surface, so that any given point in the operating surface travels, or "tracks" in constantly varying paths and does not return to the same position except after relatively long periods of time. More summarily expressed, the same point on the grinding wheel does not track twice in the same path on the work.

The grinding wheel in this illustration is secured to the armature shaft of a built-in electric motor contained in a housing 12 (Fig. 4), which is secured to, or made as part of, a swinging carrier 13 having axially alined trunnions 14 and 15 which are mounted to turn in eccentric bearing sleeves 16 and 17 respectively, supported also rotatably in bearings 18 and 19 provided in a stationary part of the machine frame structure. The trunnion axis is shown at b in Fig. 8

and the axis of the bearings 18 and 19 is shown at *c* in the same figure. One of these axes is above the other while the grinding wheel axis *A* is approximately at the same level as the trunnion axis *b*. In other words, the axes *b* and *c* lie in a plane which is substantially at right angles to, or at least makes a large angle with, the plane of the axes *A* and *b*; wherefore oscillation of the bearing sleeves moves the grinding wheel back and forth in the plane of the axes *A* and *b*. Means are provided, and will presently be described, for so oscillating the bearing sleeves. Other means are provided for swinging the holder 13 through small angles around the axis *b*, whereby to raise and lower the grinding wheel; i. e., move it in a direction substantially perpendicular to the direction in which it is moved by the oscillation of the bearing sleeves.

The means for imparting the above described movements to the grinding wheel holder are as follows. An electric motor 20 (Fig. 2) drives, by means of a belt 21 and pulley 22, a shaft 23 which is contained in a housing 24 on the machine base. Shaft 23 carries two worms 25 and 26, meshing with worm wheels 27 and 28, respectively, (Fig. 3). Worm wheel 27 is keyed to a shaft 29 on which a cam 30 is splined. A rod 31 (Fig. 5) mounted for endwise movement, but withheld from rotation, in a guide 32 carries a roll 33 on one end which bears on cam 30, and its other end has rotative bearing in, and a thrust shoulder 34 bearing against, a worm or screw 35 which is splined to an adjusting shaft 36 and is pressed toward cam 30 by a spring 37 reacting against a stationary abutment 38. Shaft 36 supports and guides worm 35, and also serves as a means by which angular adjustment may be manually imparted to the worm at need.

A gear or worm wheel 39 (Fig. 9) underlies and meshes with the worm 35 and is secured to a shaft 40 which extends inwardly from the housing 24 and carries a cam 41 on its inner end (Fig. 7) beneath the carrier 13, and on which a projection 42 thereof rests.

It will be evident from the foregoing that the slowly rotating cam 30 reciprocates the worm 35 and, through the latter and gear 39, oscillates cam 41. Any desired extent, rate and timing of movement may be imparted through this mechanism to the grinding wheel carrier by appropriate design of the worm and wheel gearing 25-27 and of the cam 30. Fig. 9 shows illustratively one suitable form of such cam, which has a single throw of gradual and continuous rise and descent. Fig. 10 shows an alternative cam 30a having five symmetrical lobes. Any other form of cam may be substituted for these.

The worm wheel 39, previously mentioned, is secured to a shaft 43, on the inner end of which is a cam 44. This cam oscillates the bearing sleeves 16 and 17 through a follower roll 45 pivoted at an intermediate point on a bar 46 which is secured at its ends to arms 47 and 48 which are rigidly connected, or integral, with the bearing sleeves 16 and 17 respectively. A spring 49 acts in conjunction with gravity to hold the roll 45 against cam 44.

The sleeves 16 and 17, arms 47 and 48, and bar 46 constitute a yoke pivoted in aligned bearings and having eccentric bearings for the grinding wheel carrier, so arranged with respect to the actuating cam 45 that the oscillative movement imparted by the latter causes shifting of the grinding wheel in the prescribed direction.

The cams 30 and 44 cooperate in giving a re-

sultant movement to the grinding wheel, compounded of movements in paths at right angles to each other, or approximately so, and in the plane of rotation of the wheel, or substantially parallel to the path in which the work-contacting part of the wheel travels. It is preferred that the ratios of the two worm and wheel pairs (25-27 and 26-28) be prime to one another to prevent synchronous operation of the cams 30 and 44 and cause a longer wandering period of the grinding wheel before returning to a previous position than would be the case otherwise.

However, it is within my contemplation to put either cam 30 or 44 out of action. To this end the cams are splined on their respective shafts and the cam 30 is movable endwise by a shifter fork 51 carried by an endwise movable rod 52 having a handle 53, while the cam 44 is similarly movable by a fork 54 carried by a slide rod 55 which has a handle 56. Associated with cam 30 is a concentric circular disk 57 against which the roll 33 bears when this cam is out of action; and a similar disk 58 is associated with cam 44 to support the yoke 46 when cam 44 is out of action, or, in place of the disks 57 and 58, cams of different form than the cams 30 and 44 respectively may be provided, whereby to vary the motions of the grinding wheel without need of removing the cams from their shafts.

An alternative, or additional, means for preventing duplications of wheel tracking is shown in Figs. 11, 12 and 13. Here the shaft 23 is divided into two sections 23a and 23b, on the contiguous ends of which are secured electromagnetic clutch elements 60 and 61 of known character. These clutches are in circuit with a switch 64 which is adapted to be opened by a circuit breaker 62 carried by a lever 63 pivoted on the housing structure. A disk 64 is secured to shaft 29 and has a circumferential undercut groove 65 in which studs 66 are adjustably mounted. One arm of lever 63 extends into the path of these studs and is displaced by them as they pass. This opens switch 64 frequently and briefly, causing the clutches to be deenergized and enabling the shaft section 23a to shift angularly with respect to shaft section 23b, thus changing the timing of the cams controlled by these respective sections. Otherwise, the combination including the divided shaft, clutch, and clutch-controlling means may be the same as previously described.

In the generic aspects of the invention the grinding wheel *G* represents and typifies any abrading tool, of whatever material made and whether a rotating disk adapted to make contact on a lateral face with the work, or a wheel adapted to bear at its circumference, or a tool of other form which is moved for cutting otherwise than rotatably about an axis. The electric motor, previously described as built into the housing 12, and of which the field coil 67, armature 68 and armature shaft 69 are represented diagrammatically in Fig. 7, typifies any operative means for imparting the prescribed cutting movement to the abrading tool. The principles illustrated in the herein described embodiment of the invention may be applied in many diverse forms and environments, all of which are included within the scope of protection herein claimed.

What I claim and desire to secure by Letters Patent is:

1. In an abrading machine, a supporting structure, a bearing sleeve rotatively mounted in said structure and having an internal bearing eccentric

tric to the axis about which the bearing is constrained to turn, a carrier having a pivot rotatively fitted to said internal bearing, an abrading element mounted on said carrier at a distance from said pivot and on a radius thereof which makes a large angle with the line of centers of the external and internal bearings of said sleeve, a cam acting on said carrier in a manner to turn the same about the axis of said pivot, an arm connected to said bearing sleeve, a cam acting on said arm with ability to rotate the sleeve about its own axis, and mechanism for simultaneously driving said cams.

2. In an abrading machine, the combination with a constantly traveling abrading tool and means for imparting cutting travel thereto, of mechanism for preventing the same points on the abrading tool from constantly tracking in the same paths, comprising a rotatively mounted pivot support, a carrier for the abrading tool having a pivotal connection with said pivot support on an axis eccentric to the axis of the support, the abrading tool being mounted on said carrier on a radius of the pivotal connection which lies at a large angle to the shortest line between the said pivot axis and the axis of said pivot support, an arm connected to said pivot support, a cam acting on said arm for imparting oscillative movement thereto, a cam acting on said carrier for imparting oscillative movement to the carrier around the pivotal axis thereof, and means for rotating said cams simultaneously at different speeds.

3. In an abrading machine, the combination with a constantly traveling abrading tool and means for imparting cutting travel thereto, of mechanism for preventing the same points on the abrading tool from constantly tracking in the same paths, comprising a rotatively mounted pivot support, a carrier for the abrading tool having a pivotal connection with said pivot support on an axis eccentric to the axis of the support, the abrading tool being mounted on said carrier on a radius of the pivotal connection which lies at a large angle to the shortest line between the said pivot axis and the axis of said pivot support, an arm connected to said pivot support, a cam engaged with said arm, a cam engaged with said carrier, worm gears in rotation-transmitting connection with the respective cams, a drive shaft, and worms carried by said shaft each meshing exclusively with one of said worm gears.

4. In the combination set forth in claim 2, means for disengaging one of said cams from the part of the mechanism on which it acts.

5. In the combination set forth in claim 3, means for disengaging one of said cams from the portion of the mechanism on which it acts.

6. In an abrading machine having a shiftable abrading tool carrier, a means for moving said carrier comprising a cam, mechanism for rotating the cam, an endwise movable shaft bearing on said cam and movable endwise thereby, a worm in thrust transmitting alinement with said shaft, a gear meshing with said worm and rotatable about an axis transverse to the line of movement of the previously named shaft, and a cam coupled to said gear and arranged to impart movement to said carrier.

7. In an abrading machine, the combination with a constantly traveling abrading tool and means for imparting cutting travel thereto, of mechanism for preventing the same points on the abrading tool from constantly tracking in the same paths, comprising a rotatively mounted pivot support, a carrier for the abrading tool having a pivotal connection with said pivot support on an axis eccentric to the axis of the support, the abrading tool being mounted on said carrier on a radius of the pivotal connection which lies at a large angle to the shortest line between the said pivot axis and the axis of said pivot support, an arm connected to said pivot support, a cam engaged with said arm, a cam engaged with said carrier, worm gears in rotation-transmitting connection with the respective cams, alined shaft sections, worms carried by each of said sections, one of which meshes with one of said worm gears and the other with the other worm gear, disconnectible clutch means coupling said shaft sections together, and means operated by the mechanism for periodically disconnecting and reconnecting said clutch means to cause a change in the angular relationship of said cams to one another.

8. In an abrading machine, the combination with a constantly traveling abrading tool and means for imparting cutting travel thereto, of mechanism for preventing the same points on the abrading tool from constantly tracking in the same paths, comprising a rotatively mounted pivot support, a carrier for the abrading tool having a pivotal connection with said pivot support on an axis eccentric to the axis of the support, the abrading tool being mounted on said carrier on a radius of the pivotal connection which lies at a large angle to the shortest line between the said pivot axis and the axis of said pivot support, an arm connected to said pivot support, a cam engaged with said arm, a cam engaged with said carrier, worm gears in rotation-transmitting connection with the respective cams, alined shaft sections, worms carried by each of said sections, one of which meshes with one of said worm gears and the other with the other worm gear, disconnectible clutch means coupling said shaft sections together, means operated by the mechanism for periodically disconnecting and reconnecting said clutch means to cause a change in the angular relationship of said cams to one another, an electromagnetic clutch between said shaft sections for transmitting rotation from one to the other, a switch in circuit with said clutch, and means driven by a part of the mechanism for opening and closing said switch.

9. In a machine of the character set forth, an abrading tool, a carrier for said tool having alined pivots, eccentric bushings in which said pivots are contained, the plane which contains the abrading tool axis and the pivot axis being at a large angle with the plane of said pivot axis and the axis of the eccentric bushings, arms protruding from said bushings, a bar secured to said arms, and an actuating member arranged to exert force on said bar to move the bushings angularly about their axis and thereby shift the pivots of the tool carrier.

WALTER F. ROSS.
